COVER FOR A FILTER

Herbert G. Kamrath, Barrington, R. I., assignor to Fram Corporation, a corporation of Rhode Island

Application November 2, 1951, Serial No. 17,239

Term of patent 14 years

(Cl. D46—1)

To all whom it may concern:

Be it known that I, Herbert G. Kamrath, a citizen of the United States, residing at Barrington, in the county of Bristol and State of Rhode Island, have invented a new, original, and ornamental Design for Cover for a Filter, of which the following is a specification, reference being had to the accompanying drawing, forming part thereof.

Fig. 1 is a top plan view of a cover for a filter, showing my new design;

Fig. 2 is a side elevation thereof.

I claim:

The ornamental design for a cover for a filter, as shown.

HERBERT G. KAMRATH.
